HIS ATTORNEY

UNITED STATES PATENT OFFICE

WILLIAM M. BIDDLE, OF CAMDEN, NEW JERSEY, ASSIGNOR TO TURN-RITE PROCESS CO., INC., OF PHILADELPHIA, PENNSYLVANIA, A CORPORATION OF DELAWARE

SHOE LAST

Application filed August 26, 1930. Serial No. 477,821.

This invention relates to shoe lasts, and has for an object to provide a last especially, though not exclusively, adapted for the first lasting operation of a turned shoe construction.

A further object of the invention is to provide along the sides of a last, recesses for receiving the excess area of the quarter or upper over the lining in a turned shoe, so that the turned shoe may be made with the quarter larger than the lining, so that the two will properly co-act when the shoe has been turned.

It is well known, that in the present practice of making a turned shoe, it is necessary to make the lining of greater area than the quarter, for the reason that, in the initial stages, the shoe is constructed inside out, and the lining must be of such area as to enclose the outer sheet of material. This results in a shoe giving the lining an inclination to wrinkle which is difficult to overcome.

The invention is directed to other objects and possesses other features of novelty and advantage, some of which, together with the foregoing, will be hereinafter more fully set forth.

In the drawings:

Figure 1 is a view of the improved last, in side elevation,

Figure 2 is a view of the last, in top plan,

Figure 3 is an inverted plan view of the last, and

Figure 4 is a sectional view, taken on line 4-4 of the several preceding figures.

Like characters of reference indicate corresponding parts throughout the several views.

The present invention, therefore, comprises a last having upon opposite sides, grooves A, located adjacent to the heel, and extending vertically throughout the extent. At the upper end at 10, this groove A is relatively narrower and shallow, forming at the top of the last, a tongue-like part 11. At the bottom, the grooves A are relatively wide and deep, as indicated at 12. Also, preferably these grooves are set with their major axes at an inclination to the vertical. The posterior margin of the grooves at the top being slightly

nearer the posterior side of the last than the posterior side at the bottom. At the posterior extreme, the last is provided with a concave part 13 in place of the usual convex, or relatively straight construction. This concavity 55 is for the purpose of receiving and accommodating the counter which is ordinarily skived at its opposite edges, forming a bulge at the central part, which thus fits into the concavity provided.

Also, the bottom of the last is slightly convexed, as indicated at 14, and the upper part 15, is made slightly narrower or thinner than customary.

Of course, the shoe last, herein illustrated, 65 may be modified in various ways without departing from the invention herein set forth and hereinafter claimed.

The last is not limited to any particular use, but one manner of using is disclosed in 70 the copending application for "Turned shoe and method of making" Serial No. 477,822, filed on even date herewith.

The invention is hereby claimed as follows:

1. A shoe last having grooves formed in the sides adjacent the heel part, and extending from top to bottom.

2. A shoe last having grooves formed in the sides adjacent the heel part, said grooves being tapered in extent, and extending from top to bottom.

3. A shoe last having grooves formed in the sides adjacent the heel part and extending from top to bottom, said grooves being wider 85 and deeper adjacent the sole part than at the top.

4. A shoe last having a posterior concaved throughout substantially its entire vertical extent.

5. A shoe last having the posterior side formed as an inwardly extending curve with its limits substantially at the top and bottom of the last.

6. A shoe last provided with a concavity in 95 its posterior end, said concavity being upon an arc, the cord of which cuts the arc substantially at the top and bottom of the last.

7. A shoe last having its posterior formed as a concave with substantially vertically 100

trending spaced grooves upon opposite sides of such concave position, said grooves being wider adjacent the sole of the last than at the top.

8. A shoe last having a concave posterior part, approximately vertical grooves spaced upon opposite sides adjacent the concave part, and a sole part convex upon transverse plane.

9. A shoe last having grooves formed in the opposite sides adjacent the heel, said grooves extending substantially perpendicular to the plane of the heel.

10. A shoe last having grooves formed in opposite sides adjacent the heel, the major axes of which extend substantially perpendicular to the plane of the heel, said grooves being wider at the bottom than at the top.

11. A shoe last having grooves formed in opposite sides adjacent the heel, the major axes of said grooves being approximately perpendicular to the plane of the heel, the margins of said grooves converging upwardly and the major axes also converging upwardly.

25. In testimony whereof I have signed my name to this specification.

WILLIAM M. BIDDLE.
